ADJUSTABLE MOUNTING FOR WALL
SWITCH BOXES AND SIMILAR RECEP-
TACLES

Edward F. Kenna, Hoboken, N. J.

Application January 5, 1932, Serial No. 584,794

7 Claims. (Cl. 247—22)

This invention relates generally to the mounting of wall boxes used to hold electrical switches, receptacles, side wall brackets and similar equipment, and is specifically designed to provide a simple, inexpensive, and universal mounting for a standard type of such wall boxes now quite generally used and hereinafter described.

The type of box referred to is provided with certain laterally projecting lugs which are now usually fastened to built-up horizontal wooden strips extending from stud to stud for the mounting of boxes in vertical positions, or to horizontal wooden strips with vertical wooden strips set in between for mounting boxes in horizontal positions, both of which procedures consume a lot of time. Other supports not allowing adjustment of position, either horizontal or vertical, or of the mounting of boxes in gangs, have also been usually employed heretofore.

My present invention provides a simple, standardized set of supporting apparatus by which such standard wall boxes can be quickly and neatly mounted in any of the standard lath and plaster wall structures, in any desired location and position, horizontal or vertical. Also, by my invention single boxes or boxes in gangs of two, three or more can be easily and quickly installed, so that the saving in time needed by the electrician for doing the work will more than equal the cost of such apparatus.

The best form of apparatus at present known to me embodying my invention is illustrated in the accompanying two sheets of drawings in which

Fig. 1 is a front elevation showing the switch box installed in one position, parts of the supporting structure being broken away.

Fig. 2 is a similar view showing the box installed in another position.

Fig. 3 shows a modification.

Fig. 4 is a cross section on line 4—4 of Fig. 1 on an enlarged scale, and

Fig. 5 is a front elevation of a gang box with a portion of the supporting structure.

Throughout the drawings like reference characters indicate like parts. 1, 1, represent portions of the studding usually employed in building partition walls of lath and plaster. In the preferred form of my invention I employ metal rods 2, 2, which are made of proper length to be fastened across between two adjacent portions of the elements of the studding, as shown in Figs. 1 and 2, in parallel position. 3, 3, represent generally a standard form of wall switch box now quite generally used, and the particular embodiment

of my invention here illustrated is specifically designed for use with this type of box, but of course the principle of the invention could be equally well applied to other constructions of wall boxes or similar containers with slight modifications of the details of construction here shown and described.

Referring to the box 3, the details of its construction are as follows: The bottom of the box is formed by a strip of metal 4, the ends of which are turned up at 5, 5, to form the box ends. 8, 8, are the side plates which are held to the box ends by the construction best shown in Fig. 4, where 9 is a lug bent inward from one end of each side plate, leaving recess 10 beside it in the end of the plate, into which recess fits a similar lug 11 bent out and around from the box end 5, and having beside it a notched or cut away portion 12 into which the lug 9 is nested. The said plates 8, 8, are duplicates, each having on one end the lug 9 above described and shown at the right hand side of Fig. 4, while its other end has a wide notch 13 stamped in it, as shown at the left-hand side of Fig. 4, and a slightly dished-in portion 14 in the bottom of this notch into which may nest the fastening screw 7, which is screwed into the lug 6, formed on the box and projecting into notch 13. These boxes as now marketed are also provided with angle lug members 15, 15, held on either end of the box by setscrews 17, 17, engaging the slotted feet 16, 16, of said angle lug members 15.

The box construction above described constitutes no part of my invention, said invention relating to convenient means for mounting such box in any position and such invention consists essentially in the combination with the box of the pivoted clamps represented generally by 18, 18, which are adapted to embrace the rods 2 and slide along same, or be fastened in any position thereon.

The preferred construction of such clamps here shown comprises two similar jaw members 19, 19, which are formed by cutting a narrow strip of metal into sections of the proper length and bending one end of each section into half-round shape to produce the similar semicircular recesses 20, so that when two of said jaws are placed together, in the position shown in Fig. 4, and held together by any convenient fastening means, an efficient form of clamp is produced. The straight portion of each clamp member 19 is perforated at two points, one near the curved jaw end to receive the clamping screw 22, and the other near the opposite end of the

jaw member to receive the pivot screw 21. The angle lug member 15 being then perforated to receive the pivot member 21 at any desired point, the clamp may be pivotally mounted on said lug 5 15 and swung either into the position in Fig. 2 so that when grasping the rods 2 the box 3 has its major axis extending at right angles to said rods or, when swung into the position shown in Fig. 1, said clamps may also grasp said rods and 10 then hold the box in position with its major axis parallel to said rod. To permit of the last described arrangement the clamps 18 of course must be of such length that when swung into the position shown in Fig. 1 the clamping jaws will 15 project beyond the planes of the side walls of the box. If the pivot members 21 are also screws the clamps can be fastened in any position of angular adjustment by setting up said screws.

23, 23, represent lugs on the box ends as now 20 marketed which can be used for fastening flush switches, receptacles, or bridges (side wall brackets) for supporting wall fixtures in position.

Fig. 5 shows the manner in which my invention may be used in installing what is known as a 25 gang box which is simply an elongated box produced by combining parts of several of the standard boxes shown in Figs. 1, 2 and 4. Thus by removing the right hand side plate 8 from one box, the lefthand side plate from another such 30 box and both said side plates from a third box, the three may be combined, as shown in Fig. 5, to form a gang box, the length of which is equal to three times the width of the standard box, while the width of said gang box is equal to the 35 length of the standard box. The end sections of the constituent boxes are fastened together by sliding the depressed lug 6 of one box end partly under the lug 11 of the adjacent box end and then nesting the setscrew 7, carried by lug 40 6 of one box end, in the recess 12 opposite the lug 11 of the adjacent box end and setting up setscrew 7. The structure so produced can be supported by my clamps 18, 18, one being mounted at each corner of the gang box on an angle lug member 15, as before, swung into proper position and clamped in that position.

The mode of operation of the invention has been previously described in substance. The rods 2, 2 are fastened to the studding at the proper 50 distance apart, the clamps 18, in partly open condition, are pivotally mounted on the angle lug members 15 and swung into proper positions to grasp the rods and the clamp screws 22 set up far enough to ensure said clamps holding 55 on the rods. The box may then be shifted lengthwise of the rods until the correct position in the wall is attained and thereafter the screws 21 and 22 are set up firmly so as to cause the clamps to frictionally grasp the rods and hold 60 the box in that position.

It is evident that the several portions of the foregoing operations may be quickly performed by any workman who is capable of boring holes in wood and putting in screws and that the entire operation can be quickly performed and will ensure an exact locating of the wall switch, receptacle and side wall outlet boxes in any desired position. The elements of the combination constituting my invention can be very cheaply manufactured as standard metal strips can be used for making the clamps which can be cut out and stamped into form at one operation in a press, and of course the screws and rods are of standard commercial form which can be bought in quantity at low cost.

Various changes could be made in the details of the apparatus disclosed herein, as the preferred form of my invention, without departing from the underlying principle thereof as above explained and pointed out in the appended 80 claims.

When walls are to be tiled or where boxes are to be used for base receptacles, both of which conditions require boxes to extend out further from the studding on account of the extra distance to the finished surfaces of the tiles or base, a sleeve 30 of proper length is inserted between lug 15 and the pivoted clamp 18, as shown in Fig. 3. A longer screw 21 is then used. Thus the box may be set out farther from the studding so as to still be flush with the finished surface of the tiles or base.

When it is desirable to support the ends of the cut sections of wooden lathing left on either side of the box, I employ the lath support shown in Fig. 2, which is also slidingly mounted on rods 2, 2, as there shown. This comprises an elongated U-shaped clip 31, the free ends of which are forced together by screw bolt 32 so as to clamp the cut lath ends 33, 33, between the legs 400 of the clip 31.

To render this convertible for use with both vertically and horizontally arranged boxes, it is made long enough for the former but also provided with an extra set of screw holes 34, 34, 405 through which screw 32 is inserted when the device is used with horizontally arranged boxes. To get rid of the extra then unused length of clip legs, they are each given a reduced cross section just beyond holes 34, as indicated at 35, 35, so that they may be easily broken off at those points by bending them sharply at said points, leaving the short clamp for use as shown in Fig. 1.

Having described my invention, I claim: 415

1. The combination of an electrical equipment wall box, having a plurality of projecting lugs on its exterior, with an adjacent rod fastened to the wall structure, and a two-part clamp pivotally mounted so as to swing in a plane parallel to the bottom wall of the box on each said lug and extending at right angles to and frictionally grasping said rod, each of said clamps having a length such that when it is swung to a position parallel to an end wall of said box its jaws will 120 extend beyond the plane of an adjacent side wall thereof.

2. A combination such as defined in claim 1 in which each of said lugs is perforated and each of said two-part clamps comprises duplicate members each formed out of an integral strip of metal bent to half round shape at one end to serve as a jaw and provided at other points with similarly located spaced-apart perforations, a pivot member extending through the pair of perforations 125 furthest removed from said jaws and through said lug perforation, and a clamping screw extending through the pair of perforations adjacent said jaws.

3. A combination such as defined in claim 1 140 in which each of said lugs is perforated and each of said two-part clamps comprises duplicate members each formed out of an integral strip of metal bent to half round shape at one end to serve as a jaw and provided at other points with similarly 145 located spaced-apart perforations, a pivot member extending through the pair of perforations furthest removed from said jaws and through said lug perforation, and a clamping screw extending through the pair of perforations adjacent 150

- said jaws, said pivot member also being screw-threaded.
4. The combination, with the studding of a building partition wall, of a pair of parallel rods having their ends fastened to adjacent elements of said studding, a wall box for containing electrical switches or the like equipment which has projecting, perforated lugs on its opposite ends, a plurality of clamps pivotally mounted on said lugs so as to each swing in a plane parallel to the bottom wall of said box and having jaws partly surrounding said rods and means for causing said clamps to frictionally engage said rods.
5. The combination with an electrical equipment wall box, a pair of parallel rods fastened to the studding of a building partition wall, a plurality of laths fastened to said studding and extending parallel to said rods, and means for supporting said box between said rods at a point between the cut ends of said laths, of a plurality of clips each composed of a flat strip of metal bent to a U-shape midway of its length so that its two halves extend parallel one to the other and far enough apart to permit said clips to be hooked over one of said rods with its free ends extending along either side of said laths and beyond the other rod, said free ends being perforated to receive a bolt for clamping them onto said laths, together with a screw bolt extending through said perforations for such purpose. 80
6. A combination such as defined in claim 5 in which the side members of said clips are each deeply scored at a point midway of their length; as and for the purpose set forth. 85
7. The combination, with an electrical equipment wall box, having perforated projecting lugs on opposite ends, of perforated clamps adapted to grasp parallel supporting rods, screw bolts passing through said perforations in lugs and clamps, and spacing sleeves surrounding said bolts and each held between a lug and a clamp. 90
